(57) CLAIM

The ornamental design for a can end, as shown and described.

DESCRIPTION

FIG. 1 is a top view of a can end attached to a can body according to our new design;

FIG. 2 is a top perspective view of a can end unattached to a can body according to our new design;

FIG. 3 a front elevation view thereof, the front elevation view being identical to the rear, left side, and right side elevation views

FIG. 4 is a top view thereof;

FIG. 5 is a bottom view thereof; and,

FIG. 6 is a bottom perspective view thereof.
